[57] ABSTRACT

A clocked bootstrap inverter circuit including an inverting amplifier, an active load for the inverting amplifier including a capacitive bootstrapping circuit, a biasing circuit responsive to a first clocking signal and a second clocking signal 180° out of phase with the first clocking signal, and an amplifier disabling device responsive to a third clocking signal which is more than 180° out of phase with the first clocking signal. The biasing circuit alternately activates and inactivates the active load while the disabling device alternately disables the amplifier and provides a small time delay for allowing the bootstrapping circuit to be pre-charged.

CLOCKED BOOTSTRAP INVERTER CIRCUIT

RELATED APPLICATIONS

The present invention is related to the inventions disclosed in my previous applications entitled, "An Improved MOS Bootstrap Inverter Circuit," U.S. Pat. Ser. No. 176,128, filed Aug. 30, 1971, and "Isolated Bootstrap Inverter Circuit," U.S. Pat. Ser. No. 182,717 filed Sept. 22, 1973, both of which are assigned to the assignee of the present invention.

SUMMARY OF THE PRESENT INVENTION

The present invention relates generally to bootstrap inverter circuits and more specifically to clocked bootstrap inverter circuits having particular application in MOSFET integrated circuits.

The presently preferred embodiment of the present invention includes a first FET providing an inverter responsive to an input signal, a second FET providing an active load for the inverter, a capacitor providing a bootstrapping circuit for the active load, a third FET responsive to a first clocking signal and operative to bias the active load conductive, a fourth FET responsive to a second clocking signal and operative to bias the active load nonconductive, and a fifth FET responsive to a third clocking signal and operative to disable the inverter. In an alternate embodiment, the third and fourth FETs are replaced by a single FET which is at all times biased conductive and responds to the first clocking signal to alternately bias the active load conductive and nonconductive.

Among the advantages of the present invention is that the power consumed during the operation of the device is substantially reduced by an amount proportional to the duty cycle of the first clocking signal.

Other advantages of the present invention will no doubt become apparent to those of ordinary skill in the art after having read the following detailed disclosure of the preferred embodiments which are illustrated in the several figures of the drawing.

IN THE DRAWING

FIG. 1 is a schematic diagram of a clocked bootstrap oscillator circuit in accordance with the present invention;

FIG. 2 is a timing diagram illustrating operation of the preferred embodiments of the present invention;

FIG. 3 is a schematic diagram of an alternative embodiment of a clocked bootstrap inverter in accordance with the present invention.

DETAILED DESCRIPTION OF THE PREFERRED EMBODIMENTS

Referring now to FIG. 1 of the drawing, a presently preferred embodiment of a clocked bootstrap circuit is illustrated. The circuit includes an inverting amplifier formed by a field effect transistor (FET) T₁, an active load for transistor T₁ formed by an FET T₂, a clocked biasing circuit for transistor T₂ including a pair of FETs T₃ and T₄, a capacitor C forming a bootstrapping feedback path for transistor T₂ and a clocked amplifier disabling means formed by an FET T₅.

The drain 10 of transistor T₁ is coupled to a circuit node 12, which also serves as the output terminal for the circuit, while the drain 14 is coupled to a circuit ground (a first source of potential V_{ss}) at 16. The circuit input signal V_{in} is applied to the gate 18 of transis-

tor T₁ via input terminal 19. The drain 20 of transistor T₂ is coupled to a second source of potential V_{dd} at terminal 22 while its source 24 is coupled to circuit node 12. A capacitor C provides a bootstrapping feedback circuit coupling the gate 26 of transistor T₂ to circuit node 12.

The drain 28 of transistor T₃ is coupled to V_{dd} at terminal 22 while its source 30 is coupled to a circuit node 32 (at the gate 26 of transistor T₂). The gate 34 of transistor T₃ is periodically energized by a first clocking signal V_{φ1}. The drain 36 of transistor T₄ is coupled to circuit node 32 while its source 38 is coupled to circuit ground at 16. The gate 40 of transistor T₄ is periodically energized by a second clocking signal V_{φ̄1} which is 180° out of phase with the first clocking signal V_{φ1}.

Transistor T₅ has its drain 42 coupled to circuit node 12 and its source 44 coupled to circuit ground at 16 while its gate 46 is energized by a third clocking signal V_{φ̄2} delay which is a delayed version of clocking signal V_{φ1}.

The phase angle between V_{φ1} and V_{φ̄1} delay is selected sufficiently larger than 180° to enable capacitor C to be charged to (V_{dd}-V_T) before transistor T₅ is rendered nonconductive.

Transistor T₁ responds to the input signal V_{in} to develop an output signal V_{out} at node 12 for driving the external load 50. Transistor T₂ and capacitor C, of course, provide a bootstrapped active load for transistor T₁, the bootstrapping action providing for high speed circuit operation. The function of the clocked biasing circuit formed by transistors T₃ and T₄ is to limit the power consumption of the overall circuit by periodically disabling the active load transistor T₂ so that the average power consumed by the circuit is reduced. More specifically, the average power consumed by the circuit is proportional to the duty cycle of the first clocking signal V_{φ1}.

Transistor T₅ acts as an inverter disabling device and serves to maintain node 12 at V_{ss} for a selected delay period during which capacitor C is charged to approximately (V_{dd}-V_T) and transistor T₂ is thereby rendered conductive as the potential at node 32 moves toward (V_{dd}-V_T). V_T is the threshold potential of transistor T₃. At a predetermined time following the initiation of the charging cycle for capacitor C, transistor T₅ is rendered nonconductive by the clocking signal V_{φ̄2} delay thereby allowing node 12 to move toward V_{dd}. As this occurs, bootstrapping capacitor C causes circuit node 32 to be charged to approximately (2V_{dd}-V_T).

Referring now additionally to the operation of the circuit in FIG. 2 of the drawing will be described in detail. In FIG. 2 the clocking signals V_{φ1}, V_{φ̄1}, and V_{φ̄2} delay are shown at 60, 62, and 64 respectively, V_{in} is illustrated at 66, the potential developed at node 32 is shown at 68, and the output signal V_{out} is shown at 70.

With the various illustrated signals applied, the circuit at time t₀, it will be noted that transistor T₁ is initially biased conductive by V_{in} thereby making V_{out} = V_{ss}, transistor T₂ is nonconductive since transistor T₃ is nonconductive and transistor T₄ is conductive thereby pulling the gate 26 of transistor T₂ to V_{ss}, and transistor T₅ is also biased conductive.

If now, at time t₁, V_{in} changes state, so as to cause transistor T₁ to be rendered nonconductive, the output signal V_{out} will not change since transistor T₅ is still

conductive and holds V_{out} at the potential V_{ss} . However, at time t_2 , the clocking signals V_{Φ_1} and $V_{\Phi_1^-}$ begin to change state causing transistor T_3 to become conductive and transistor T_4 to become nonconductive. As indicated by curve 68, this causes node 32 to be pulled to approximately $(V_{dd} - V_r)$. Note that for a short period of time following t_2 , node 12 is held at V_{ss} by transistor T_5 so as to allow capacitor C to be charged to $(V_{dd} - V_r)$. After the predetermined delay period, typically about 40 nanoseconds, transistor T_5 is rendered conductive as $V_{\Phi_1^-}$ delay changes state and bootstrapping action, effected as node 12 begins to move toward V_{dd} , causes the conductivity of transistor T_2 to be further increased to decrease the time required to pull node 12 to V_{dd} .

At time t_4 , clocking signals V_{Φ_1} , and $V_{\Phi_1^-}$ again change state causing node 32 to be pulled to V_{ss} , thereby discharging capacitor C and rendering transistor T_2 nonconductive. V_{out} , however, remains at V_{dd} until time t_5 when transistor T_5 is rendered conductive to pull node 12 to V_{ss} . This operation will, of course, be repeated each time clocks V_{Φ_1} and $V_{\Phi_1^-}$ change state so that the average power consumed by the circuit will be proportional to the duty cycle of V_{Φ_1} .

Although in the clocked bootstrap circuit an additional component of power dissipation is added due to capacitive charging and discharging, the total power dissipation can be considerably reduced (compared to a DC bootstrap circuit) if the duty cycle is kept small and the frequency of V_{Φ_1} is relatively small. Note that the output signal V_{out} will have a pulsed configuration during the time that the inversion of input signal V_{in} occurs.

In FIG. 3 of the drawing an alternative embodiment of the present invention is shown which requires one less component to achieve similar results to those obtained in the previously described embodiment. As in the previous embodiment, this circuit includes an inverting FET T_{10} , an active load FET T_{20} , a clocked biasing FET T_{30} for biasing transistor T_{20} and a gating FET T_{50} . Note that the principle differences between this circuit and that of FIG. 1 are that the fourth biasing transistor T_4 is omitted and the clocking signal V_{Φ_1} is applied to the drain 128 of transistor T_{30} while the gate 134 thereof is coupled to V_{dd} at terminal 122.

The operation of this circuit can likewise be described with reference to FIG. 2 of the drawing since the clocking input signals V_{Φ_1} and $V_{\Phi_1^-}$ delay are identical to those of the FIG. 1 embodiment. At some time t_0 with V_{in} applied to the base 118 of transistor T_{10} and the clock potentials V_{Φ_1} and $V_{\Phi_1^-}$ delay having the states indicated at 60 and 64, transistor T_{10} and transistor T_{50} are both conductive so that the potential V_{out} at node 112 is at circuit ground (V_{ss}). Transistor T_{30} is also conductive since V_{dd} is applied to its gate 134. This pulls the potential at node 132, and hence, gate 126 of transistor T_{20} , to V_{ss} so that transistor T_{20} is nonconductive.

To indicate that in these circuits the timing of V_{in} is not necessarily fixed with respect to the clocking signals, V_{in} is selected so that it changes state at a time t_{3a} (see dashed curve 166) instead of at time t_1 as in the previous example. This being the case, note that even though transistor T_{20} is rendered conductive at time t_2 and transistor T_{50} is rendered nonconductive at time t_3 , the output signal V_{out} does not begin to change state until V_{in} changes state at time t_{3a} , as indicated by the

dashed line 170. At time t_4 , it will be noted that since a potential of V_{dd} (where V_{Φ_1} has an amplitude of V_{dd}) is applied to drain 128 of transistor T_{30} , the charge on capacitor C₁ will be approximately $(V_{dd} - V_r)$, since transistor T_{30} is always conductive, and will remain at that potential until time t_{3a} when transistor T_{10} is rendered nonconductive allowing node 112 to be pulled to V_{dd} through the conductive transistor T_{20} , thereby causing node 132 to be raised to $(2V_{dd} - V_r)$ due to the bootstrapping action of transistor C_1 .

As in the previous embodiment, transistor C_1 will be discharged as V_{Φ_1} changes state at time t_4 . This will, of course, cause transistor T_{20} to be rendered nonconductive. However, V_{out} will remain at V_{dd} until time t_5 when $V_{\Phi_1^-}$ delay changes state to pull V_{out} to V_{ss} . V_{out} will then continue to change state between V_{dd} and V_{ss} responding to T_{10} until V_{in} changes state, at which time V_{out} will be held at V_{ss} until V_{in} again changes state.

Although this circuit has the advantage that fewer FETs are required for its implementation, it is also subject to the disadvantage that it is more prone to lateral PNP action occurring on the MOS chip. To avoid this disadvantage, it is necessary that the circuit layout be carefully chosen to avoid such harmful PNP action.

Alternatively, the critical nodes can be surrounded by p-diffused regions which are tied to V_{dd} to provide a PNP path to V_{dd} thus reducing the probability of PNP action between the critical nodes and the rest of the circuit.

Although the present invention has been described above with particular reference to p-channel embodiments, as may be inferred from the illustrated signal polarities, it will be appreciated that the disclosed principles can likewise be applied to n-channel devices. In addition, the capacitors C and C_1 can be made in the form of a standard MOS capacitor or can be formed by the gate-to-channel capacitance of an additional FET in accordance with the teachings of my above referenced copending application entitled, "An Improved MOS Bootstrap Circuit."

Moreover, while the present invention has been described with reference to certain preferred embodiments, it is contemplated that additional alterations and/or modifications thereof will no doubt become apparent to those of ordinary skill in the art after having read the foregoing description. Accordingly, it is intended that the appended claims be interpreted as covering all such alterations and modifications as fall within the true spirit and scope of the invention.

What is claimed is:

1. A clocked bootstrap inverter circuit comprising a first source of potential; a second source of potential; an inverting amplifier having an output terminal, and being responsive to an input signal and operative to develop an output signal at said output terminal, said amplifier including a first FET having a first gate for receiving said input signal, a first source coupled to said first source of potential and a first drain coupled to said output terminal; an active load means for said amplifier including a bootstrapping circuit, said load means having a conductive state and a nonconductive state, said load means including a second FET having a second gate, a second source coupled to aid output terminal and a second drain coupled to said second source of potential;

biasing means responsive to a first clocking signal and operative to render said load means alternately conductive and nonconductive, said biasing means including a third FET and a fourth FET, said third FET having a third gate for receiving said first clocking signal, a third source coupled to said second gate, and a third drain coupled to said second source of potential, said fourth FET having a fourth gate for receiving a second clocking signal which is 180° out of phase with said first clocking signal, a fourth source coupled to said first source of potential and a fourth drain coupled to said second gate; and

disabling means responsive to a third clocking signal and operative to periodically disable said amplifier, 15 said disabling means including a fifth FET having a fifth gate for receiving said third clocking signal, a fifth source coupled to said first source of potential, and a fifth drain coupled to said output terminal, said third clocking signal being more than 180° 20 out of phase with said first clocking signal.

2. A clocked bootstrap inverter circuit comprising a first source of potential; a second source of potential;

an inverting amplifier having an output terminal, and 25 being responsive to an input signal and operative to develop an output signal at said output terminal, said amplifier including a first FET having a first gate for receiving said input signal, a first source coupled to said first source of potential and a first 30 drain coupled to said output terminal;

an active load means for said amplifier including a bootstrapping circuit, said load means having a conductive state and a nonconductive state, said load means including a second FET having a second gate, a second source coupled to said output terminal and a second drain coupled to said second 35 source of potential;

biasing means responsive to said first clocking signal and operative to render said load means alternately 40 conductive and nonconductive,

said biasing means including a third FET having a third gate coupled to said second source of potential, a third source coupled to said second gate, and a third drain for receiving said first clocking signal; 45 and

disabling means responsive to a second clocking signal and operative to periodically disable said amplifier.

3. A clocked bootstrap inverter circuit as recited in 50 claim 2 wherein said disabling means includes a fourth FET having a fourth gate for receiving said second clocking signal, a fourth source coupled to said first source of potential, and a fourth drain coupled to said output terminal, said second clocking signal being 55 more than 180° out of phase with said first clocking signal.

4. A clocked bootstrap inverter circuit comprising

a first source of potential; a second source of potential; an inverting amplifier having an output terminal, and being responsive to an input signal and operative to develop an output signal at said output terminal; an active load means for said amplifier including a bootstrapping circuit, said load means having a conductive state and a nonconductive state; said load means including a first FET having a first gate, a first source coupled to said output terminal, and a second drain coupled to said second source of potential;

biasing means responsive to a first clocking signal and operative to render said load means alternately conductive and nonconductive, said biasing means including, a second FET responsive to said first clocking signal and operative to couple said first gate to said second source of potential, and a third FET responsive to a second clocking signal and operative to couple said first gate to said first source of potential, said second clocking signal being 180° out of phase with said first clocking signal; and

disabling means responsive to a third clocking signal and operative to periodically disable said amplifier, said disabling means including a fourth FET responsive to said third clocking signal and operative to couple said output terminal to said first source of potential, said third clocking signal being more than 180° out of phase with said first clocking signal.

5. A clocked bootstrap inverter circuit comprising a first source of potential; a second source of potential;

an inverting amplifier having an output terminal, and being responsive to an input signal and operative to develop an output signal at said output terminal; an active load means for said amplifier including a bootstrapping circuit, said load means having a conductive state and a nonconductive state, said load means including a first FET having a first gate, a first source coupled to said output terminal, and a first drain coupled to said second source of potential;

biasing means responsive to a first clocking signal and operative to render said load means alternately conductive and nonconductive, said biasing means including a second FET having a second gate coupled to said second source of potential, a second source coupled to said first gate, and a third drain for receiving said first clocking signal;

disabling means responsive to a second clocking signal and operative to periodically disable said amplifier, said disabling means including a third FET responsive to said second clocking signal and operative to couple said output terminal to said first source of potential.
